Primary Examiner — Paula Greene

(57) **CLAIM**

The ornamental design for an earmuff assembly having an integrated cellular phone earpiece, as shown.

DESCRIPTION

FIG. 1 is a right perspective view thereof;

FIG. 2 is a left perspective view thereof;

FIG. 3 is a right side elevation view thereof; and,

FIG. 4 is a front side elevation view thereof.

1 Claim, 2 Drawing Sheets

FIG. 1

FIG. 2

FIG. 3

FIG. 4
